UNITED STATES PATENT OFFICE.

ARTHUR B. FLAGG AND WALTER H. LIVERMORE, OF WORCESTER, MASSACHUSETTS,
ASSIGNORS, BY MESNE ASSIGNMENTS, TO LIVERMORE PAY STATION COMPANY,
OF PORTLAND, MAINE, A CORPORATION OF MAINE.

COIN-CONTROLLED PAY-STATION FOR TELEPHONES.

1,112,370.

Specification of Letters Patent.

Patented Sept. 29, 1914.

Application filed December 26, 1905. Serial No. 293,175.

To all whom it may concern:

Be it known that we, ARTHUR B. FLAGG and WALTER H. LIVERMORE, both citizens of the United States, residing at Worcester, in the county of Worcester and Commonwealth of Massachusetts, have invented a new and useful Improvement in Coin-Controlled Pay-Station for Telephones, of which the following is a specification, accompanied by drawings forming a part of the same, in which—

Figure 1 represents a rear view of a telephone pay station embodying our invention and having the back removed to disclose the interior mechanism. Fig. 2 is a similar view but having the rear coin channel plate removed showing the coin separator and the channel separating plate. Fig. 3 is a similar view having the rear channel plate removed and the channel separating plate and coin separator removed in order to disclose the recessed side of the front channel plate. Fig. 4 is a vertical sectional view through the channel plates on line 4—4, Fig. 1. Fig. 5 is a transverse sectional view through the channel plates on line 5—5, Fig. 1. Fig. 6 is a side elevation of the coin separator. Fig. 7 is a top view of the coin separator. Fig. 8 is an end view of the coin separator. Fig. 9 is a transverse sectional view of the coin separator on line 9—9, Fig. 6. Fig. 10 is a rear elevation having the back of the case and the channel plates removed to disclose the resonant gong plate, and Fig. 11 is a side elevation shown in central vertical section, on line 11—11, Fig. 1.

Similar reference letters and figures refer to similar parts in the different views. Our present invention relates to a coin controlled pay station to be used in connection with the sound transmitting apparatus of a telephone, and our invention is especially designed for the payment of tolls of different values by the use of a single pay station.

Our improved apparatus comprises a coin channel for the reception of coins of different values in the payment of telephone tolls, a separator by which the coins are separated according to their respective denominations, individual channels for the separated coins leading to signal devices, with means for transmitting the signals to

the central office; and our invention has for its objects to enable tolls of different values to be paid by the employment of a single coin receiving slot or channel; to effect a separation of the coins according to their respective values in order that the admission of each individual coin may be indicated by its appropriate signal; to produce an audible signal by the different coins in their passage through the apparatus without a material deflection in the path of the coin; to reduce the transmission of sound from the moving coin within the coin channels, and to increase the transmission of sound from the sound signals, and these objects among others we accomplish by the construction and arrangement of parts as hereinafter described and pointed out in the annexed claims.

As illustrated in the accompanying drawings, our improved device comprises a box 1 inclosing the coin channels and the sound signaling apparatus. Within the box are posts 2, 2, more clearly shown in Fig. 11, to which are attached the channel plates 3 and 4, with intervening washers 5 of felt, vulcanized fiber, or other sound nonconducting material, in order to check the transmission of sound caused by the moving coin from the channel plates to the posts 2. The top of the box 1 is provided with a slit 6 and a projecting slotted plate 7 through which coins are admitted to a channel 8 formed between the channel plates 3 and 4. The upper end of the channel 8 is considerably wider than the thickness of the coin to be admitted, and a short distance below the top of the box the channel is contracted to form shoulders 9 which are curved or inclined to the line of movement of the coin in the coin channel, one of these shoulders is shown in Figs. 2 and 3. The object of these shoulders is to check the movement of the coin as it passes to the contracted space in the channel and thereby preventing an undue momentum from being imparted to the coin by the operator. The shoulders 9, 9, as shown in Fig. 11, are beveled so that if the movement of a coin should be checked by one of the shoulders the coin will slide by gravity into the contracted portion 10 of the channel. After passing the shoulders 9 the coin is deflected from a right line and caused to pass around

a raised boss 11 designed to still further retard the movement of the coin as it enters the upper end of the coin separator. The coin channel 8 lies in a vertical plane so that a coin in passing through the contracted and inclined portion 10 of the channel will be supported by and roll upon its edge, being held in a vertical position by the side walls of the channel except as it 10 may be slightly deflected by its passage around the raised boss 11. The coin separator is clamped between the channel plates 3 and 4, and it consists of an inclined trough 12 open at the top and substantially 15 triangular in cross section. The rear side of the coin separator or that lying next the channel plate 4 is shown in Fig. 2, by the withdrawal of the channel plate 4, and the front side of the coin separator lying 20 next the channel plate 3, is represented in Fig. 6.

Below the coin separator or trough 12 we insert a separator plate 13 by which the channels formed in the plates 3 and 4 are 25 separated, so as to form two sides of the channels leading downward through the channel plates from the trough 12. The trough 12 is provided with openings in its sides to permit the coins entering the upper 30 end of the trough to be deflected and pass through the openings and fall into the coin channels upon one side or the other of the separator plate 13. The front side of the trough 12 is provided with an opening 14 35 through which coins of the largest diameter are deflected into a coin channel 15 formed in the channel plate 3, and through which the coin descends in front of the separator plate 13. The trough 12 is also provided 40 on its front side with an opening 16 through which coins of the next size are deflected into the coin channel 17 formed in the channel plate 3, through which the coins descend in front of the separator plate 13. 45 The opposite or rear side of the trough 12 is provided with an opening 18 through which the third size of coins are deflected to the rear of the separator plate 13 into a coin channel 19 formed in the channel plate 4, 50 the sides of said channel being indicated by the broken lines 20, Fig. 1. The rear side of the trough 12 is also provided with an opening 21 through which the fourth size of coins is deflected through an opening 22 55 in the channel plate 4 and be caused to fall outside the channel plate into a receptacle 23. Coins which are too small in diameter to be deflected through either of the four openings in the trough 12 roll entirely through 60 the trough and are delivered through an opening 24 in the bottom of the trough into a coin channel 25, shown in Fig. 1 as inclosed between the broken lines 26. The trough 12 is therefore capable of controlling 65 the movement of coins of five different di-

ameters, such for example as pieces of the following denominations, namely, fifty cents, twenty-five cents, five cents, one cent, and ten cents, said coins being delivered from the trough 12 in the order named, corresponding to their diameters, a fifty cent coin being delivered through the opening 14 into the coin channel 15 of the plate 3, and a twenty-five cent piece being delivered through the opening 16 into the coin channel 17 of the plate 3, both of said coins being delivered through a common spout 27 into the coin receptacle 23.

A five cent piece is delivered through the opening 18 into the coin channel 19, the one cent piece is delivered through the openings 21 and 22 outside the channel plate 4 and allowed to fall into the receptacle 23, while the ten cent piece continuing through the trough 12 falls by gravity through the opening 24 into the coin channel 25. Both the five cent piece passing through the channel 19 and the ten cent piece passing through the channel 25 are delivered through a common spout 28 into the coin receptacle 23.

The trough 12 when held between the channel plates 3 and 4 is supported with its front side 29 next the channel plate 3 in a vertical position, as shown in Fig. 8, and with its rear side 30 in an inclined position, 95 so that a coin entering the upper end of the trough 12 will be tipped and raised against the inclined side 30 of the trough.

Extending across the top of the trough are a series of curved deflectors 31, 32, 33 and 34 placed at successively decreasing distances above the bottom of the trough, the first deflector 31 being arranged to strike the upper edge of the largest coin or fifty cent piece and deflect it toward the side 29 of the trough and through the opening 14. The deflector 32 is at a less height from the bottom of the trough and arranged to contact with the next size of the coin or the twenty-five cent piece and deflect it through the opening 16. The third deflector 33 is adapted to contact with the top of a five cent piece and deflect it against a projecting spur 35 which causes the coin to swing slightly on its base and drop through the opening 18 105 in the side 30 of the trough. In their passage through the trough 12 the coins roll on their edges over the bottom of the trough in a slightly tipped position, resting on their sides against the inclined side of the trough. The first opening in the trough is intended 110 to allow the passage of coins of the largest diameter, the second opening those of the next smaller diameter, and so on. If the openings in the sides of the trough were circular, it is obvious that the smaller coins would pass through any larger opening to which they might be presented, as for instance, by the tipping of the apparatus, and no separation of the coins would be accom- 115 120 125 130

plished. We, therefore, make the openings in the trough 12 oblong, with their minor axes less than the diameter of the coin to pass through them and with their major axes slightly greater than the diameter of the coin to pass through them. We place these openings at an oblique angle to the bottom of the trough, so the coins will slide over the openings unless the contact of a coin with its appropriate deflector causes its course to be so changed as to allow the momentum of the coin to propel it through the opening. We have found by experiment that a preferable form of these openings 14, 16, 18 and 21 is pear shape, but the essential feature is the oblong shape of the opening by which one axis is less and the other greater than the diameter of the coins. The one cent piece continuing its movement 20 is deflected by the curved deflector 34 against a similar spur 36, causing the coin to fall through the opening 21 in the side 30 of the trough, while the ten cent piece continues its movement beneath all the deflectors until 25 it falls through the opening 24 in the bottom of the trough. In order to facilitate the passage of the five and one cent coins through the openings 18 and 21, we slightly contract the width of the trough opposite 30 the openings 18 and 21 by pressing in, or recessing the vertical side 29, as shown at 29a, Figs. 6 and 7.

By the operation of the trough 12, two sizes of coins, to wit, the fifty cents and 35 twenty-five cents, are delivered through the spout 27, while the five cent and ten cent coins are delivered through the spout 28 into the coin receptacle 23, while the one cent coin falling through the opening 21 of 40 the trough and the opening 22 of the rear channel plate falls outside of the channel plates into the cash receptacle. The upper end of the coin channel 15 is slightly inclined so that the coin in entering the channel 15 will move by gravity toward an opening 37 in the side wall of the channel and at 45 a point midway the opening 37 and just outside a straight line connecting the ends 38 and 39 of the side wall, we place a wire 50 held in a bracket 41 and forming part of a coiled wire gong 42, so that a coin passing down the inclined channel 15 will be brought in contact with the wire and vibrate the gong 42, thence passing around the 55 curved portion of the channel 15 to the spout 27, in front of which is located a similar wire 43 held in a bracket 44 and forming part of a coiled wire gong 45, said coin producing two audible signals in its passage to 60 the coin receptacle 23. The twenty-five cent coin entering the channel 17 passes downward through the spout 27 and is likewise brought into contact with the wire 43, thereby producing a single sound signal.

65 The five cent coin delivered through the

opening 18 into the coin channel 19 is delivered through the spout 28 against the lower edge 46a of a bell 46, and the ten cent piece rolling through the entire length of the trough contacts with the upper edge 46b of the bell 46 and falls through the opening 24 of the trough into the channel 25 and is delivered through the opening 28 into contact with the lower edge 46a of the bell 46. The five cent piece therefore, produces 75 a single sound signal upon the bell 46, while the ten cent piece produces a double sound signal upon the same bell.

The coiled wire gongs 42 and 45 are supported by brackets 41 and 44 which are attached to the lower half of a resonant steel plate 47. The upper half of the steel plate 47 is supported upon posts 48 attached to the box 1, so that the vibrations of the gongs 42 and 45 and of the bell 46 will be conveyed to the resonant plate 47. The front side of the box 1 is provided with an opening 49 to which the base 50 of the transmitter and arm 51 is attached.

In the operation of our apparatus the sound of the moving coins within the channels of the plates 3 and 4 is prevented from being conducted through the box 1 to the telephone transmitter by the sound insulating washers 5, while the vibration of the signal gongs and bell are magnified by the vibrations of the resonant steel plate 47, causing sharp and well defined sound signals to be transmitted to the central office, distinct from any interfering sounds produced by the movement of the coins in the coin channels. Our improved apparatus enables four distinct tolls to be received at an individual pay station, namely, fifty cents, twenty-five cents, ten cents, and five cents, and this is 100 accomplished without requiring separate slots for each denomination, which is liable to lead to confusion and mistakes on the part of the operator. As all denominations of coin are entered through a single slot or opening, no mistake can be made by the operator, and each coin, whatever its denomination, is automatically conducted by the coin separating trough 12 to its proper channel, thereby unerringly controlling the 105 sound signal according to the size of the coins.

We obtain a clear and loud signal from each of the gongs and from opposite edges of the bell by placing the gong wire and the edges of the bell which are struck by the coin just outside the line of side wall of the coin channels, and beyond the path of the coin, and by providing an opening large enough to allow the forward edge of the coin to strike squarely against the wire or the bell, and we further incline the coin channels immediately in front of the gong wire or bell in order that the momentum of the rolling coin may expend its full force 130

- against the wire or bell. In sounding a signal therefore, the coin is caused to roll freely down an inclined section of the coin channel and strike the sounding device placed beyond the line of the side wall, and by a rebound be returned at an angle to the line of its former movement either into a continuation of the channel or into the coin receptacle.
- We do not herein claim the specific construction of the coin separating device, the same having been made the subject of a divisional application.
- What we claim as our invention and desire to secure by Letters Patent is:—
1. The combination with a pair of coin channel plates recessed in opposite directions and placed face to face to form a coin channel, of a separator plate parallel with the recessed sides of said channel plates and held between said plates in the center of the channel, whereby said channel is divided into two parts.
  2. The combination with a pair of coin channel plates, recessed in opposite directions and placed face to face to form a coin channel, of a separator plate parallel with the recessed sides of said channel plates and inserted in the center of the lower part of the channel, whereby said channel is divided into two parts, with said separator plate forming the inner sides of said channels, and with said channels communicating with the single channel at the upper part of the channel plates.
  3. The combination of a pair of recessed channel plates placed face to face to form a single coin channel, a trough for the passage of coins therethrough having a series of side openings and placed in said coin channel, and a separator plate placed in the center of the coin channel and below said trough, and coin separating devices whereby the coins are diverted from the trough and through said side openings and upon opposite sides of said separator plate.
  4. The combination of a pair of channel plates having recessed sides and placed face to face to form a coin channel, one of said channel plates curved laterally outward and the other of said plates curved inward to correspond with said outward bend, and provided with a bevel to receive the advancing coin, whereby the motion of the coin is checked as it passes through said coin channel.
  5. The combination with a coin channel having its sides in a vertical plane and having a section with its edges inclined, whereby a coin will roll on its edge through said inclined section, said channel having a reverse curved section, said inclined section with a second oppositely inclined section, an opening in said curved section in the line of movement of the coin, and a sound signal placed opposite said opening and outside the coin channel, whereby the coin by its rolling action through the first inclined section will be forcibly carried against the sound signal and caused to rebound into the second and oppositely inclined section.
  6. In a telephone pay station, the combination with a sound transmitter, of a resonant plate attached to the base of said transmitter, a sound signal device attached to said resonant plate, and a coin channel plate independent of said resonant plate.
  7. In a telephone pay station, the combination with a support for a coin channel plate, of a coin channel plate held on said support, sound insulating material between said channel plate and its support, a sound signal device, a sound transmitter and a connection for the delivery of sound waves from said sound signal device to said transmitter.
  8. In a telephone pay station, the combination with a box or case, a coin channel plate inclosed in said box, and sound insulated therefrom, a resonant plate supported by said box, a sound signal device supported by said resonant plate, and a telephone transmitter attached to said resonant plate.
  9. In a telephone pay station, the combination with a box or case, of a channel plate inclosed therein, a resonant plate independent of said channel plate, a sound signal device supported by said resonant plate, and a telephone transmitter attached to said resonant plate.
  10. In a telephone pay station, the combination of a coin channel plate, a resonant plate having an independent support from said channel plate, a telephone transmitter attached to said resonant plate, and a sound signal device having a metallic connection with said resonant plate.
  11. In a telephone pay station, the combination with a box containing a sound signal device, and a coin channel arranged to conduct a coin into contact with said sound signal device, of a resonant metal plate within said box separated from said coin channel and having a metallic connection with said sound signal device, and a metallic connection between said resonant plate and the transmitter of a telephone.
  12. In a telephone pay station, the combination with a box containing a sound signal device and a resonant plate having a metallic connection with said sound signal device and with the transmitter of a telephone, of means separate from said resonant plate for conducting a coin against said sound signal device.
  13. In a telephone pay station, the combination with a box containing a resonant plate, of a metallic connection between said plate and the transmitter of a telephone, and means for producing sound vibrations

in said resonant plate by the passage of a coin through said box without contact with said resonant plate.

14. In a telephone pay station, the combination with a sound transmitter, of a resonant plate having a metallic connection with said transmitter, a sound signal device attached to said resonant plate, and means separate from said resonant plate for conducting a coin against said sound signal device.

15. In a telephone pay station, the combination with a box containing a resonant metallic plate, means for supporting said

plate from a portion of its surface, leaving 15 the remainder of said plate free to vibrate, a telephone transmitter having a metallic connection with the free portion of said plate, and means for producing sound vibrations in said free portion by the passage of a coin 20 through said box without contact with said plate.
